UNITED STATES PATENT OFFICE.

WARREN MILLER, OF MURPHYSBORO, ILLINOIS.

BALING-PRESS.

SPECIFICATION forming part of Letters Patent No. 693,729, dated February 18, 1902.

Application filed November 16, 1901. Serial No. 82,560. (No model.)

To all whom it may concern:

Be it known that I, WARREN MILLER, a citizen of the United States, residing at Murphysboro, in the county of Jackson, State of Illinois, have invented certain new and useful Improvements in Baling-Presses, of which the following is a specification, reference being had therein to the accompanying drawings.

This invention relates to baling-presses, and particularly to a self-baling device actuated by the plunger of the press.

The invention has for an object to present an improved construction of parts wherein the feed of the bale-tie wire by the movement of the plunger in completing the bale automatically throws into operation the feeding-needle, the holding devices, and the twisting-fingers.

A further object of the invention is to provide an improved construction of driving mechanism for the bale-tie devices which is adapted to be automatically thrown out of operation by the plunger-driving means and into operation in the rotation of the spool carrying the baling-wire.

Another object of the invention is to provide an improved construction of needle for carrying the tie-wire through the bale-box and for severing the wire held by the needle.

Other and further objects and advantages of the invention will be hereinafter set forth and the novel features thereof defined by the appended claims.

In the drawings, Figure 1 is a plan view of a press having the invention applied thereto. Fig. 2 is a vertical section on the line 2 2 of Fig. 1. Fig. 3 is a partial side elevation with the twisting mechanism removed. Fig. 4 is a vertical section through the bale-box on the line 4 4 of Fig. 1. Fig. 5 is a horizontal longitudinal section. Fig. 6 is a detail perspective of one end of a needle, and Fig. 7 is a diagram showing the positions of the tie-wire relative to the bale-box and other parts.

Like letters of reference refer to like parts in the several figures of the drawings.

The letter A designates a base having thereon a baling-box A', provided with a hopper A², beneath which a plunger B, provided with a knife-edge B', is located. This plunger is connected to a driving device by means

of the pitman B², extending to the crank-arm B³, which is adapted to be driven by any suitable power—for instance, by the application of a lever, as shown at B⁴—and is supported by a frame B⁵. All of these parts may be of any suitable construction and configuration, and the base may be mounted in any desired manner either for transportation or cooperation with an adjacent machine.

The baling-box A' is provided at opposite sides with springs A³, adapted to seat in recesses B⁶, as shown in Fig. 2, when the plunger B passes the springs to hold any baled material which has been forced beyond the springs.

Upon the base of the machine a wire-reel C', carrying the tie-wire C, is pivotally mounted and may be removed by opening the hinged keeper C², as shown in Fig. 1. The wire C is carried through a guide C³ to the needles D, which are intermittently reciprocated to pass the wire across the bale-box. The wire-reel is of suitable diameter to complete one revolution, as each bale is formed in order that the controlling-lever C⁴, carried by the axis C⁵ of the wheel, may engage and operate a releasing device for the driving-shaft, to be hereinafter described.

Any desired number of needles D may be used; but two are here shown mounted in the frame D', which is slidably supported upon ways D² and operated by means of a lever D³, extending from the crank-wheel D⁴, carried upon the driving-shaft E. This crank-wheel is also provided upon one face with a segmental series of gear-teeth D⁵, coöoperating with a gear F for actuating the holding devices. The gripping-jaws of these needles comprise a fixed jaw D⁶, upon which a movable cutting-jaw D⁷ is pivotally mounted, as at D⁸, and the movement thereof limited by a pin D⁹ upon the fixed jaw and projections D¹⁰ upon the cutter. The end of the needle is tapered, as shown at D¹¹, and adapted to enter a recess G' in the cutter-plate G, which forces the jaws of the needle together, thus severing the wire held thereby. The plate G is suitably mounted in a fixed position upon the base in alinement with the needles at one extreme of their movement. Upon the base of the machine adjacent to the frame D' a

suitable counter G^3 may be secured and actuated by a pin G^4 , carried in the movement of the frame.

The wire-holding device consists of a notched plate F' , mounted relatively to a pair of toothed wheels F^2 , the teeth of which pass over said notches and engage the wire disposed therein to hold the same against movement. These wheels are rotated at the desired intervals by the gear F , carrying a pin F^3 , which engages the sliding bar F^4 , held by keepers F^5 and provided with pins F^6 to engage the teeth of the wheels in order to rotate the latter in the reciprocation of the bar F^4 . This bar is restored to its normal position by means of a spring F^7 , mounted upon a fixed part.

Lying opposite the holding-wheels and in the path of travel of the wire twisting-fingers H are provided, one for each strand of wire, and are suitably mounted in a bearing H' . The end H^2 of the twisting-fingers is provided with a recess to receive the wire, and the opposite end has secured thereto a pinion H^3 , those of adjacent fingers meshing together and with a driving-pinion H^4 , carried by a counter-shaft H^5 , upon which the driving-gear F for the holding-wheels is also mounted, all of which parts are driven from the main shaft E . In order to drive this shaft intermittently or only after the bale has been formed, the driving-gear E' thereon is adapted to be thrown into and out of engagement with the segmental gear I' , carried upon the driving-wheel I . The shaft E is provided at its end beneath the baling-box with a tubular portion E^2 , adapted to contain a spring E^3 , bearing against the end of the shaft E for normally forcing the gear E' into engagement with the wheel I . Any suitable means may be provided for permitting this longitudinal movement of the tubular section and shaft. For instance, a pin E^4 may be projected into a slot E^5 , formed in the tubular sections. The shaft E is also provided with a shoulder E^6 , adapted to engage a spring-latch J , which may be thrown out of engagement with said shoulder by means of the projecting end J' , which is engaged by the lever C^4 , extending from the wire-reel. The shaft E is also provided with a plate E^7 , secured thereto and adapted to lie in contact with the apertured shifting lever E^8 , pivotally mounted at E^9 and through which the shaft E travels. It will be seen that any movement of this lever toward the plunger will carry the shaft E in that direction until the shoulder E^6 engages the spring-latch J .

For the purpose of imparting movement to the lever E^8 a cam I^2 is provided upon the periphery of the driving-wheel I , which engages and forces this lever backward. In order to prevent the accidental engagement of the pinion E' when the plunger is beyond the hopper, a spring J^2 is adapted to move laterally into contact with said pinion beyond the wheel I and is shifted out of contact there-

with by means of the projection I^3 , which engages the spring and moves the same laterally off of the shaft to leave the pinion free to move into engagement with the gear.

In the operation of the invention it will be seen that the plunger reciprocates within the press entirely independent of the other parts, as the driving-shaft for the needle, twisters, and holders is held out of gear with the wheel I by means of a spring J . At such time a single strand of wire extends across the baling-box and is held by the wheel F^2 . The continued action of the plunger collects the bale of hay and withdraws the wire from the reel, thus carrying the wire forward into the loop, as shown in Fig. 7, which action also carries the strand into the recess of the twister H . The baling action continues until the reel has made one complete revolution, when the arm C^4 thereof engages the spring J to release the shaft E and permit the spring E^3 thereof to throw the gear E' into mesh with the teeth of the driving-wheel I . Just prior to this action the projection I^3 upon the wheel engages and moves the spring J^2 from behind the gear E' . The continued rotation of the power-wheel I now drives the shaft E and the pinion D^4 , by which the needles are reciprocated and a loop of wire carried across the baling-box by each needle. In this movement the wire upon one side of the needle is placed in the holder F^2 and upon the opposite side in the twister H , while in its continued movement the needle passes through the cutter-plate G and severs the wire, thus leaving a completed wire around the bale in position to be twisted and a strand held at one end to be drawn around the bale in the advanced movement of the next bale. As shown by dotted line in Fig. 2, the teeth D^5 upon the crank-wheel D^4 extend only for a part of the circumference thereof, thus permitting the complete movement of the needles in one direction across the box before the holding and twisting devices are actuated. After the bale thus formed is completed by twisting the tie-wire the projection I^3 upon the driving-wheel I engages and shifts the lever E^8 toward the press until the shoulder E^6 engages the spring-latch J , and thus holds the pinion E' out of gear, so that the continued baling action of the plunger may proceed until the arm C^4 of the reel again engages the spring J .

It is obvious that changes may be made in the details of construction and configuration and also in the assembling and mounting of the several parts without departing from the spirit of the invention as defined by the appended claims.

Having described my invention and set forth its merits, what I claim, and desire to secure by Letters Patent, is—

1. In a baling-press, a plunger and driving means therefor, a wire-reel, a feeding-needle for the wire, a wire-twister, a driving-shaft for said needle and twister, and means carried by said reel for controlling the driving of said

shaft from the plunger-driving means; substantially as specified.

2. In a baling-press, a plunger and driving means therefor, a wire-reel, a feeding-needle for the wire, a wire-twister, a driving-shaft for said needle and twister, a latch-releasing arm carried by said reel, means for moving said shaft longitudinally, and a latch disposed in the path of said arm for holding said shaft against longitudinal movement; substantially as specified.

3. In a baling-press, a plunger and power-shaft therefor, a wire-reel, a feeding-needle for the wire, a wire-twister, a driving-shaft for said needle and twister, a latch-releasing arm carried by said reel, means for moving said shaft longitudinally, a latch disposed in the path of said arm for holding said shaft against longitudinal movement, a driving-wheel upon the plunger power-shaft adapted to rotate the driving-shaft for said needles and twisters, and a cam projection upon said wheel adapted to shift the needle-driving shaft out of contact with said wheel; substantially as specified.

4. In a baling-press, a plunger and power-shaft therefor, a wire-reel, a feeding-needle for the wire, a wire-twister, a driving-shaft for said needle and twister, a latch-releasing arm carried by said reel, means for moving said shaft longitudinally, a latch disposed in the path of said arm for holding said shaft against longitudinal movement, a driving-wheel upon the plunger power-shaft adapted to rotate the driving-shaft for said needles and twisters, a cam projection upon said wheel adapted to shift the needle-driving shaft out of contact with said wheel, wire-holding wheels, and means driven from the twisting mechanism for actuating said wheels; substantially as specified.

5. In a baling-press, a plunger, a driving means therefor, a wire-reel, means for holding the free end of the wire, a wire-needle adapted to travel across said press, twisting-fingers at the opposite side of said press from said reel, and means driven from the plunger power-shaft for successively actuating said needles and said twisting-fingers; substantially as specified.

6. In a baling-press, a plunger, a driving means therefor, a wire-reel, means for holding the free end of the wire, a wire-needle adapted to travel across said press, twisting-fingers at the opposite side of said press from said reel, a driving-shaft provided with a crank-wheel to operate said needles and having a portion of its surface provided with teeth for actuating said holding and twisting-fingers subsequent to the first movement of the needle, a spring for shifting said shaft toward the plunger-driving means, a latch for retaining said shaft against such shifting movement, and an arm carried by the wire-reel for releasing said latch; substantially as specified.

7. In a baling-press, a plunger, a driving

means therefor, a wire-reel, means for holding the free end of the wire, a wire-needle adapted to travel across said press, twisting-fingers at the opposite side of said press from said reel, a driving-shaft provided with a crank-wheel to operate said needles and having a portion of its surface provided with teeth for actuating said holding and twisting-fingers subsequent to the first movement of the needle, a spring for shifting said shaft toward the plunger-driving means, a latch for retaining said shaft against such shifting movement, an arm carried by the wire-reel for releasing said latch, a lever adapted to shift said shaft against said spring to throw the same out of gear, and means carried by the plunger-driving means for automatically operating said lever in the rotation of the shaft; substantially as specified.

8. In a baling-press, a plunger, a driving means therefor, a wire-reel, means for holding the free end of the wire, a wire-needle adapted to travel across said press, twisting-fingers at the opposite side of said press from said reel, a driving-shaft provided with a crank-wheel to operate said needles and having a portion of its surface provided with teeth for actuating said holding and twisting-fingers subsequent to the first movement of the needle, a driving-wheel for said shaft, a spring for shifting said shaft toward the plunger-driving means, a latch for retaining said shaft against such shifting movement, an arm carried by the wire-reel for releasing said latch, a lever adapted to shift said shaft against said spring to throw the same out of gear, means carried by the plunger-driving means for automatically operating said lever in the rotation of the shaft, a segmental section of driving-teeth carried by the wheel upon the plunger-driving means, a gear upon said driving-shaft for engaging said teeth, a laterally-movable spring projected into the path of longitudinal movement of said gear, and a projection carried by the wheel upon the plunger-driving shaft for shifting said spring; substantially as specified.

9. In a baling-press, a wire-carrying needle having a fixed jaw and movable jaw pivoted thereto, and means for closing said jaws to sever the wire held thereby at one extreme of the movement of the needle; substantially as specified.

10. In a baling-press, a wire-carrying needle comprising a fixed jaw and movable jaw pivoted thereto and provided with a tapered end, and a stop-pin adapted to engage projections from the movable jaw to limit the movement thereof; substantially as specified.

11. In a baling-press, a wire-holding device comprising a fixed recessed plate secured to the press, a rotatable toothed wheel adapted to travel over said recess, and a reciprocating bar having a projection to engage the wheel for intermittently rotating said wheel; substantially as specified.

12. In a baling-press, a wire-holding device

comprising a fixed recessed plate, a rotatable toothed wheel adapted to travel over said recess, a sliding bar actuated by a driving-gear, a projection carried by said bar to engage the teeth of said wheel, and a spring for restoring said bar to its normal position; substantially as specified.

13. In a baling-press, a wire-reel and wire carried thereby, a traveling needle, a cutter-plate at one extreme of the needle movement, a holding device upon one side of said plate, a twisting device upon the opposite side thereof, and means for driving all of said parts whereby a loop of wire carried by the needle may be severed, one portion thereof held and the other twisted to form a bale-tie; substantially as specified.

14. In a baling-press, a traveling needle device, a twisting device, a driving-shaft for said needle and twisting device provided with a shoulder, a crank-wheel upon said shaft for driving said needle and provided with a series of teeth for driving said twister, a latch-spring for holding said shaft out of engagement with the driving means therefor, a spring for shifting said shaft into engagement with said driving-wheel, a wire-reel, and an arm carried thereby for releasing said latch-spring from said shoulder; substantially as specified.

15. In a baling-press, a traveling needle device, a twisting device, a driving-shaft for said needle and twisting device provided with a shoulder, a crank-wheel upon said shaft for driving said needle and provided with a series of teeth for driving said twister, a latch-spring for holding said shaft out of engagement with the driving means therefor, a spring for shifting said shaft into engagement with said driving means, a wire-reel, an arm carried thereby for releasing said latch-spring from said shoulder, a power-wheel having a series of teeth for driving said shaft during a portion of its rotation, a shift-lever adapted to shift said shaft out of engagement with said wheel, and a projection carried by said wheel for engaging said lever; substantially as specified.

16. In a baling-press, a plunger and driving means therefor, a power-wheel carried by said means, a wire-reel, a traveling needle adapted to carry wire across the press, a holding-wheel for retaining the free end of the wire, a twisting device adapted to engage a portion of the wire carried by the needle, and a driving device for actuating said needles in one direction, and for driving said holding and twisting devices in the return movement of the needle; substantially as specified.

17. In a baling-press, a plunger and driving means therefor, a power-wheel carried by said means, a wire-reel, a traveling needle adapted to carry wire across the press, a holding-wheel for retaining the free end of the wire, a twisting device adapted to engage a portion of the wire carried by the needle, a driving device for actuating said needles in one direction, and for driving said holding

and twisting devices in the return movement of the needle; a cutter-plate adapted to sever the wire carried by the needle, means carried by said power-wheel for throwing the driving means for said needle, holding, and twisting devices out of driving relation, and means for restoring said shaft into driving relation with said power-wheel; substantially as specified.

18. In a baling-press, a plunger and driving means therefor, a power-wheel carried by said means, a wire-reel, a traveling needle adapted to carry wire across the press, a holding-wheel for retaining the free end of the wire, a twisting device adapted to engage a portion of the wire carried by the needle, a driving device for actuating said needle in one direction and for driving said holding and twisting devices in the return movement of the needle, a cutter-plate adapted to sever the wire carried by the needle, means carried by said power-wheel for throwing the driving means for said needle, holding, and twisting devices out of driving relation, means for restoring said shaft into driving relation with said power-wheel, a latch-spring for holding said shaft out of gear, and an arm carried by the axis of the wire-reel for releasing said spring at each rotation of the reel; substantially as specified.

19. In a baling-press, a plunger and driving means therefor, a power-wheel carried by said means, a wire-reel, a traveling needle adapted to carry wire across the press, a holding-wheel for retaining the free end of the wire, a twisting device adapted to engage a portion of the wire carried by the needle, a driving device for actuating said needle in one direction and for driving said holding and twisting devices in the return movement of the needle, a cutter-plate adapted to sever the wire carried by the needle, means carried by said power-wheel for throwing the driving means for said needle, holding, and twisting devices out of driving relation, means for restoring said shaft into driving relation with said power-wheel, a latch-spring for holding said shaft out of gear, an arm carried by the axis of the wire-reel for releasing said spring at each rotation of the reel, a pinion upon said driving-shaft, a spring-arm between said pinion and power-wheel, and means carried by said power-wheel for shifting said arm out of the path of said pinion; substantially as specified.

20. In a baling-press, a plunger and driving means therefor, a power-wheel carried by said means, a wire-reel, a traveling needle adapted to carry wire across the press, a holding-wheel for retaining the free end of the wire, a twisting device adapted to engage a portion of the wire carried by the needle, a driving device for actuating said needle in one direction and for driving said holding and twisting device in the return movement of the needle, a cutter-plate adapted to sever the wire carried by the needle, means carried by

said power-wheel for throwing the driving means for said needle, holding, and twisting devices out of driving relation, means for restoring said shaft into driving relation with said power-wheel, a latch-spring for holding said shaft out of gear, an arm carried by the axis of the wire-reel for releasing said spring at each rotation of the reel, a pinion upon said driving-shaft, a spring-arm between said pinion and power-wheel, means carried by said power-wheel for shifting said arm out of the path of said pinion, a driving-gear for said twisting device, a counter-shaft having a pin-

ion meshing with said gear, a pinion in mesh with the teeth on said needle-driving device, 15 a sliding bar for actuating said holding-wheel, and a projection carried by said last-mentioned pinion for operating said sliding bar; substantially as specified.

In testimony whereof I affix my signature 20 in presence of two witnesses.

WARREN MILLER.
